(57) CLAIM

We claim the ornamental design for pants, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of pants, showing our new design, according to the first embodiment;

FIG. 2 is a left side view thereof;

FIG. 3 is a rear view thereof; and

FIG. 4 is a right side view thereof.

FIG. 5 is a front view of the pants in FIGS. 1-4 in grayscale, according to a second embodiment;

FIG. 6 is a left side view thereof;

FIG. 7 is a rear view thereof; and,

FIG. 8 is a right side view thereof.
